UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS, IN THE STATE OF MASSACHUSETTS, SWIVEL LOOM.

1,161,345.

Specification of Letters Patent. Patented Nov. 23, 1915.

Application filed November 6, 1914. Serial No. 870,702.

To all whom it may concern:

Be it known that I, EPPA H. RYON, a citizen of the United States, residing at Waltham, in the county of Middlesex and State of Massachusetts, have invented a new and useful Swivel-Loom, of which the following is a specification.

This invention relates to a swivel loom and particularly to improvements in that type of swivel looms shown in my prior Patent, No. 753,741, issued March 1, 1904.

In this type of loom, in addition to the usual fly shuttle, there are provided a plurality of swivel shuttles arranged in two or more sets and used for weaving spots or small figures upon the face of the fabric. The swivel shuttles are supported upon a rail carried by the lay and vertically movable thereon into and out of operative position. Provision is also made for moving the rail longitudinally to vary the transverse position of the design with reference to the warp, and selective devices are employed to operate each set or bank of shuttles as necessary to produce the desired figure.

It is the principal object of my invention to simplify the construction of swivel looms of this type, particularly with reference to the mechanism for producing the vertical and longitudinal movements of the shuttle rail and for selectively reciprocating the swivel shuttles.

A further object of my invention is the provision of an improved arrangement for disconnecting the pick mechanism for the fly shuttle when the swivel shuttles are in operation.

With these and other objects in view my invention consists in certain devices, arrangements, and combinations of parts which will be hereinafter described and more particularly pointed out in the appended claims. A preferred form of my invention is shown in the drawings in which—

Figure 1 is a partial side elevation of a portion of a swivel loom with my improvements embodied therein; Fig. 2 is a front elevation of the mechanism shown in Fig. 1; Figs. 3, 4 and 5 are enlarged details of portions of the mechanism for reciprocating the swivel shuttles; Fig. 6 is an enlarged front elevation of a portion of the mechanism for moving the shuttle rail transversely of the warp; Fig. 7 is a top plan view of certain of the parts shown in Fig. 6; Fig. 8 is an

enlarged detail view of the fly shuttle pick motion, and Fig. 9 is a detail view of the selective mechanism used in connection with the reciprocation of the shuttles.

Referring to the drawings, 10 indicates a portion of the loom frame. The usual lay 11 (Fig. 1) is mounted upon swords 12 and is pivotally supported upon the frame 10 by the shaft 13. The crank shaft 14 is connected to the lay by the crank arms 15 and reciprocates the same in the usual manner. The usual fly shuttle (not shown) is thrown by a picker upon the stick 16 which is provided with a lug strap 17 and lug strap connection 18 (Fig. 8).

The pick mechanism for the fly shuttle comprises a pick lever having two arms 19 and 20. The arm 19 carries a roll 21 positioned for actuation by a pick cam 22 mounted upon the usual bottom or cam shaft 23. The arm 20 of the pick lever is provided with a laterally projecting lug 24 adapted to engage a hook-shaped projection 25 upon the upper side of the lug strap connection 18. A spring 26 is secured at its lower end to the connection 18 and at its upper end to a lug 27 (Fig. 2) fixed on the loom side. The lug strap connection 18 extends beyond the projection 25 into position for engagement by a plate 28 which is vertically movable with the shuttle rail. When the rail is moved to raised position, the connection 18 is allowed to rise under the influence of the spring 26 and is engaged by the projection 24 on the pick lever arm 20, the pick mechanism then being effective to operate the fly shuttle.

When the shuttle rail is lowered into its operative position (as shown in Fig. 2), the plate 28 depresses the lug strap connection 18 so that the projection 25 can no longer engage the lug 24, the pick mechanism being thereby rendered inoperative. I have thus provided in an exceedingly simple manner for discontinuing the operation of the fly shuttle whenever the swivel shuttles are positioned for operation. Furthermore, this provision is so directly connected with the shuttle rail that it is impossible to lower the rail to operative position without disconnecting the pick mechanism.

I will now describe the mechanism for raising and lowering the shuttle rail. Referring to Figs. 1 and 2, I have shown two sets of swivel shuttles 30 mounted upon the

shuttle rail 31 and provided with pinions 32 by which they may be moved longitudinally. It should be noted however that my present invention is not concerned with any specific 5 form of swivel shuttle or with the specific means employed for reciprocating the same, and any common or suitable form of shuttle and operating device may be used. The shuttle rail 31 is provided at each end with 10 a bracket 33 mounted on the rail and having parallel shafts 34 and 35 fixed therein. The shafts 34 and 35 at their outer ends support a casting 36 having an upwardly extending arm 37. Near each end of the rail 31 the 15 rod 34 passes freely through a sleeve 38 forming a portion of a sliding block 39 which is movable vertically in a slot 40 formed in a casting 41 rigidly secured to the lay sword 12. The vertically movable rods 20 42 have their upper ends fast in the blocks 39 and at their lower end they are pivotally connected to levers 43. A plate 28 (previously described) is secured to each rod 42 (the left hand plate and rod being shown in 25 Fig. 2). The levers 43 are fixed at one end upon a shaft 44, angularly movable in bearings supported upon the loom side. A rearwardly and upwardly extending lever 45 (Figs. 1 and 4) is also secured to the shaft 44 30 and is provided at its upper end with a roll 46 positioned to engage a cam 47 mounted upon the continuously rotating cam shaft 23. The lever 45 has a lug 48 upon one side thereof positioned to engage a latch 49 35 mounted upon a fixed pivot 50. The latch 49 is connected by a cord 51 with a Jacquard or other pattern-controlled mechanism (not shown). The normal position of the lever 45 is that shown in Fig. 4 in which position 40 it is retained by the latch 49. The forward ends of the levers 43 are then in raised position and the rods 42, the plate 28 and the shuttle rail 31 are also raised therewith. The shuttle rail is then in inoperative position, 45 and the lug strap connections engages the lugs upon the pick lever arms and thereby operate the fly shuttle.

The pattern mechanism is so timed that, when the latch 49 is lifted to release the 50 lever, the roll 46 will be in engagement with one of the points of the cam 47 (as shown in broken lines in Fig. 4). As long as the latch is held up by the pattern mechanism, the roll 46 will follow the cam 47, thereby raising and lowering the shuttle rail at each reciprocation of the lay. This operation continues until the latch is released by the pattern mechanism to again engage the lug 48 on the lever 45.

60 I will now describe the mechanism for selectively reciprocating the swivel shuttles. Referring to Fig. 2, a plurality of bell cranks 50 are mounted upon a stud 51 supported by the upwardly extending arm 37 65 of the casting 36. The depending arm of

each bell crank is connected by a rod 52 to a sliding rack or other suitable mechanism for reciprocating the swivel shuttles 30, a separate bell crank and connecting rod being provided for each bank of shuttles. The 70 horizontally extending arm of each bell crank is pivotally connected to a cap 53 mounted upon the upper end of a vertically movable rod 54. The cap and rod are screw-connected, thus providing for relative adjustment and they are retained in adjusted position by check nuts 54a. At their lower ends, the rods 54 are connected to levers 55 (Fig. 4) pivoted upon a stud 56 carried by an arm 57 secured to the shaft 44 previously 80 described.

The mechanism for operating the different rods 54 and bell cranks 50 is identical and I will describe only a single set thereof. The lever 55 has a rearwardly extending arm 58 85 (Fig. 4) carrying a roll 59 positioned within a cam groove 60 formed in the radial surface of a disk 61 loosely mounted upon the shaft 44. The disk 61 is provided with a series of recesses or notches 62 in its edge, 90 these notches being engaged by a roll 63 on a locking lever 64 carried by the lever 45. A spring 65 is connected at one end to the locking lever 64 and at the other end to the lever 45 and forces the roll 63 yieldingly 95 into one of the notches 62. Inasmuch as the levers 43 and 45 and also the arm 57 are all rigidly secured to the shaft 44 and as the cam disk 61 is yieldingly locked to the lever 45, it will be seen that the parts thus far described for reciprocating the swivel shuttles will be raised and lowered simultaneously with the shuttle rail without causing relative movement between the parts of the shuttle-reciprocating mechanism. The shape of the 100 cam groove 60 is clearly shown in Fig. 4 and it is evident that rotation of one of the disks 61 upon the shaft 44 must result in alternately raising and lowering one of the rods 54, thereby reciprocating one bank of 110 swivel shuttles.

I will now describe the devices for rotating the disks 61 and for selectively determining the time of such rotation. On the side of the disk 61 opposite to the groove 60 115 the disk is provided with a ratchet 66 (Fig. 3) engaged by a pawl 67 mounted upon one arm of a two-armed carrier 68 and forced yieldingly into such engagement by a spring 69. The other arm of the carrier 68 is pivotally connected to the lower end of a swinging plate 70 (Fig. 3) having an L-shaped slot 71 therein. A lever 72 is mounted upon a fixed pivot 73 and is provided with a transversely extended head 72a (Fig. 5) 125 through which a stud 74 extends and enters the slots 71 of the separated swinging plates 70. At its opposite end the lever 72 carries a roll 75 engaging a constantly rotating cam 76 mounted upon the cam shaft 23. A 130

slot and bolt connection is provided between the cam 76 and the cam 47, whereby they may be angularly secured to each other. Each plate 70 is yieldingly drawn toward the left by a spring 77 secured to a fixed portion of the loom and is movable in the opposite direction by a cord 78 controlled by a Jacquard or other pattern mechanism (not shown).

When the plate 70 is in the normal position shown in Fig. 9, the constantly reciprocating stud 74 is freely movable vertically along the longitudinal branch of the slot 71. When the reciprocation of a particular bank 15 of swivel shuttles is desired the plate 70 which controls that bank of shuttles is moved by the pattern mechanism from the position shown in Fig. 9 to that shown in Fig. 1, the stud 74 being thereby positioned in the 20 transverse portion of the slot 71.

At its next vertical movement the stud 74 will carry the plate 70 with it thereby moving the pawl carrier 68 (Fig. 3) and the pawl 67 to rotate the disk 61 a single step 25 forward. This angular movement of the disk 61 will result in moving the swivel shuttles in the selected bank from one end to the other of their path of travel.

To prevent possible disconnection of the 30 stud 74 and the plate 70 during the vertical movement of the plate, I provide a fixed stud 79 which engages one side of the plate 70 as the upward movement of the plate begins (Fig. 3) and thereafter prevents lateral movement of the plate relatively to the 35 stud 74. At its extreme upper end the edge of the plate 70 is provided with a cut away portion 80 which permits lateral movement of the plate when in its normal lowered position.

A screw 81 is mounted in each plate 70 near its lower end and constitutes an adjustable stop for determining the normal vertical position of the plate, the screw 81 45 coöperating for this purpose with a lug 82 upon the carrier 68 (Figs. 1 and 3). A coiled spring 83 is secured at one end to the lever 72 and at its opposite end to a fixed portion of the loom, said spring being effective to move the stud 74 to its lower position and to cause the roll 75 to follow the outline of the cam 76 during its idle movements.

Referring now to the devices for longitudinally moving the shuttle rail, I have provided a bell crank 90 (Fig. 2) mounted upon an extension 91 of the casting 41. The depending arm 92 of the bell crank 90 carries a rear projection 93 positioned between vertical surfaces formed upon a casting 94 secured to the rod 34, the parts 93 and 94 forming a sliding connection between the bell crank and the shuttle rail. The laterally projecting arm of the bell crank 90 is pivotally connected to a cap 96 threaded upon

the upper end to a rod 97 and secured in adjusted position thereon by a check nut 98. At its lower end the rod 97 is pivotally connected to a lever 99 (Fig. 6) mounted upon a fixed pivot 100 and having an upwardly 70 projecting arm 101 movable therewith. The arm 101 is provided with downwardly converging surfaces 102—103 positioned for engagement by pins 104 mounted in a rotatable disk 105. A plurality of pins 104 are 75 provided and each pin is adjustable in substantially radial slots in the disk 105. The pins 104 may be provided with rolls if so desired. Upon its side opposite to the pins 104 the disk 105 is provided with a plurality 80 of rearwardly projecting pins 106 (Fig. 7) corresponding in number to the pins 104 and positioned for engagement by a pawl 107. The pawl 107 is pivotally connected to a lever 108 mounted upon a fixed pivot 85 109 and carrying a roll 110 positioned to engage the cam 47 previously described. As the roll 110 is forced outward by the cam 10 the pawl 107 will be actuated to feed the disk 105 one step in the direction of the arrow 90 shown in Fig. 6, thereby positioning the next successive pin 104 between the converging surfaces 102 and 103. The normal position of the disk is shown in Fig. 1 in which a pin 104 is positioned between the 95 inner end portions of surfaces 102 and 103, thus locking the arm 101 from movement in either direction.

The disk 105 is yieldingly held in its normal position by a spring pressed roll 111 100 (Fig. 6) mounted upon an arm 112 yieldingly forced against the disk by a coil spring 113. The lever 108 has a projection 114 formed on one side thereof, said projection being connected by a cord 115 with a Jacquard or other pattern mechanism. A coil 105 spring 116 is inserted between the pawl 107 and the projection 114 the spring forcing the pawl yieldingly upward to engage the pins 106. After the roll 110 has been forced 110 to the right (as viewed in Fig. 6) by the cam 47 it will remain in its outward position until moved inward by the pattern mechanism. The inward movement of the roll 110 is accompanied by an outward movement of 115 the pawl 107 to engage the pin 106 next in order. The pins 104 may be placed in any desired order and at any desired distances from the center thereby permitting a considerable number of different transverse positions of the figures with reference to the warp.

The operation of my improved swivel loom mechanism has been fully set forth in connection with the detailed description 125 thereof and further explanation is considered unnecessary.

Having thus described my invention it will be evident that many changes and modifications can be made therein by those skilled

in the art without departing from the spirit and scope thereof as set forth in the claims, and I do not wish to be otherwise limited to the details herein disclosed, but

5. What I do claim is:—

1. A swivel loom having, in combination, a plurality of swivel shuttles, a shuttle rail, and means to raise and lower said rail, said means including an operating lever, a cam 10 to move said lever, and a pattern controlled latch effective to normally maintain said lever in inoperative position with the rail raised.

2. A swivel loom having, in combination, 15 a plurality of swivel shuttles, a shuttle rail, and means to raise and lower said rail, said means including an operating lever mounted upon a fixed pivot, a continuously rotated cam for operating said lever, a latch to prevent said lever from following the cam, and pattern controlled means for moving said latch to release said lever.

3. A swivel loom having, in combination, 25 a plurality of swivel shuttles, a shuttle rail, and means to raise and lower said rail, said means including an operating lever, a cam to move said lever, and a pattern controlled latch effective to normally maintain said lever in inoperative position with the rail 30 raised, said latch being raised at predetermined times such that the lever when released will be in engagement with a point on said cam, said lever thereafter following said cam to lower and raise said rail.

35 4. In a swivel loom, a fly shuttle, a picker stick to throw said shuttle, a cam-operated pick lever, a connection loosely supported at one end on said stick and having its opposite end movable into and out of engagement 40 with said pick lever, and means connected with the shuttle rail for positioning said connection.

45 5. In a swivel loom, a fly shuttle, a picker stick to throw said shuttle, a cam-operated pick lever, a connection loosely supported at one end on said stick and having its opposite end movable into and out of engagement 50 with said pick lever, a spring to move said connection into engagement with said lever, and means connected with the shuttle rail effective to move said connection out of such engagement.

55 6. In a swivel loom, a fly shuttle, a picker stick to throw said shuttle, a cam-operated pick lever, a connection loosely supported at one end on said stick and having its opposite end movable into and out of engagement 60 with said pick lever, a spring to raise said connection into engagement with said lever, and a member movable vertically with the shuttle rail and effective to move said connection downwardly out of engagement with said lever.

7. In a swivel loom, a shuttle rail, a lever 65 to raise and lower said rail, a plurality of

levers to reciprocate the swivel shuttles, and a movable pivot for said last named levers controlled as to position by the first named lever.

8. A swivel loom having, in combination, 70 a plurality of swivel shuttles, a shuttle rail, means to raise and lower said rail, including an operating lever and a cam for moving said lever, a plurality of levers operable to reciprocate the swivel shuttles, and an arm 75 supporting said levers, said arm being movable with the first named lever when the rail is raised or lowered.

9. In a swivel loom, in combination, a plurality of swivel shuttles, a rail supporting 80 said shuttles, and means to move said rail longitudinally, said means including a lever having a pair of converging guiding surfaces, and a disk having a plurality of pins thereon, said pins being movable successively between said surfaces to vary the 85 position of said shuttle rail.

10. In a swivel loom, in combination, a plurality of swivel shuttles, a rail supporting 90 said shuttles, and means to move said rail longitudinally, said means including a lever having a pair of converging guiding surfaces, a single set of pins movable successively between said surfaces to vary the 95 position of said lever and rail, and pattern-controlled means for moving said pins.

11. In a swivel loom, in combination, a plurality of swivel shuttles, a rail supporting 100 said shuttles, and means to move said rail longitudinally, said means including a lever having a pair of converging guiding surfaces, and a single intermittently rotatable member effective to coöperate with said surfaces to vary the angular position of 105 said lever.

12. In a swivel loom, in combination, a plurality of swivel shuttles, a rail supporting 110 said shuttles, and means to move said rail longitudinally, said means including a lever, connections between said lever and 110 said rail, and a single rotatable member movable successively into different positions and effective to move and retain said lever in different angular positions, thereby varying the longitudinal position of said rail. 115

13. In a swivel loom, in combination, a plurality of swivel shuttles, a rail supporting 120 said shuttles, and means to move said rail longitudinally, said means including a lever, connections between said lever and 120 said rail, and a single rotatable member movable successively into different positions and effective to retain said lever in different angular positions thereby varying the longitudinal position of said rail, said member 125 positively locking said lever against movement in either direction, in each successive position.

14. In a swivel loom, in combination, a 130 swivel shuttle, and means to reciprocate said

shuttle, said means comprising a rotatable cam, devices for intermittently partially rotating said cam, a continuously-moving cam-actuated operating member, and a pattern-controlled connection between said member and said devices.

15. In a swivel loom, in combination, a swivel shuttle, and means to reciprocate said shuttle, said means comprising shuttle-moving devices, a continuously-moving cam-actuated operating member, and a pattern-controlled connection between said member and said devices, said connection having an L-shaped slot therein, and being movable by 15 said pattern-controlled mechanism to position said cam-actuated member in either the longitudinal or the transverse portion of said slot.

16. In a swivel loom, in combination, a swivel shuttle, and means to reciprocate said shuttle, said means comprising shuttle-moving devices, a lever connected to said devices, a lever-operating cam intermittently rotatable in a single direction, and pattern-controlled means for intermittently partially rotating said cam.

17. In a swivel loom, in combination, a swivel shuttle, and means to reciprocate said shuttle, said means comprising shuttle-moving devices, a lever connected to said devices, a lever-operating cam intermittently rotatable in a single direction, pattern-controlled means for intermittently partially rotating said cam, and a yielding stop effective to 35 prevent accidental displacement of said cam.

18. In a swivel loom, in combination, a swivel shuttle, and means to reciprocate said shuttle, said means comprising shuttle-moving devices, a lever connected to said devices 40 and having a roll mounted on one end thereof, a rotatable disk having a groove in its radial surface coöperating with said roll and having notches in its edge coöperating with a spring-pressed positioning device, and pattern-controlled means for intermittently 45 partially rotating said disk.

19. In a swivel loom, in combination, a swivel shuttle, and means to reciprocate said shuttle, said means comprising shuttle moving devices, including a pivoted plate having an L-shaped slot with a longitudinal and a transverse branch and a constantly reciprocated pin extending into said slot, said 50 plate being movable by pattern controlled mechanism to position said pin in either

branch of said slot, and said pin being effective when in the transverse branch to move said plate longitudinally.

20. In a swivel loom, in combination, a swivel shuttle, means to reciprocate said shuttle comprising shuttle moving devices including a pivoted plate having an L-shaped slot with a longitudinal and a transverse branch, and a constantly reciprocated pin extending into said slot, said plate being 60 movable by pattern controlled mechanism to position said pin in either branch of said slot, and said pin being effective when in the transverse branch to move said plate longitudinally, and a fixed stop positioned adjacent said plate and effective to prevent displacement of said pin out of said transverse slot during longitudinal movement of said plate.

21. In a swivel loom, in combination, a swivel shuttle, and means to reciprocate said shuttle comprising shuttle-moving devices, a rotatable member for operating said devices, means to intermittently partially rotate said member comprising a pawl, a pawl carrier 80 and a plate connected to operate said carrier and pawl and having an L-shaped slot therein, pattern-controlled means to position said plate, and means for moving said plate including a lever having a pin freely 85 movable in said slot when positioned in one branch thereof and effective to move said plate to reciprocate said shuttles when positioned in the other branch thereof.

22. In a swivel loom, in combination, a swivel shuttle, and means to reciprocate said shuttle comprising shuttle-moving devices, a rotatable member for operating said devices, and means to intermittently partially rotate said member, said means comprising 90 a pawl, a pawl carrier, a plate connected to operate said carrier and pawl, pattern-controlled means to position said plate, and means to move said plate to reciprocate said shuttle, said plate having an adjustable stop 95 thereon coöperating with said pawl carrier 100 to position said plate vertically.

In testimony whereof I have hereunto set my hand, in the presence of two subscribing witnesses.

EPPA H. RYON.
